UNITED STATES PATENT OFFICE.

WILLIAM F. MINNICK, OF NILES, OHIO, ASSIGNOR TO THE HARRIS AUTOMATIC PRESS COMPANY, OF NILES, OHIO, A CORPORATION OF OHIO.

CLAMP FOR PRINTING-PLATES.

1,091,152.

Specification of Letters Patent. Patented Mar. 24, 1914.

Application filed October 16, 1911. Serial No. 654,979.

To all whom it may concern:

Be it known that I, WILLIAM F. MINNICK, of Niles, in the county of Trumbull and State of Ohio, have invented certain new and useful Improvements in Clamps for Printing-Plates; and I do hereby declare the following to be a full, clear, and exact description of the invention, such as will enable others skilled in the art to which it appertains to make and use the same.

The primary object of this invention is to provide an extremely simple and inexpensive clamp for securing stereotype or electrotype plates to the bed of a printing press, whether flat or cylindrical, and to enable such clamps to be readily inserted and removed from the bed. And a further object is to provide a clamp by which a plate may be secured without danger of buckling.

20 The invention will be hereinafter fully set forth and particularly pointed out in the claims.

In the accompanying drawings, Figure 1 is a top plan view of a portion of a printing press form-cylinder showing a portion of a plate held by my improved clamps. Fig. 2 is an enlarged transverse sectional view of a portion of the plate and form-cylinder with the clamp in position. Fig. 3 is a similar view taken through the clamp. Fig. 4 is a longitudinal sectional view on line 4—4, Fig. 3. Fig. 5 is a view of a device for removing the clamp. Figs. 6 and 7 show a slight modification.

35 In carrying out my invention, the bed of the printing press, which may be either flat or cylindrical, is provided with a series of grooves to accommodate the clamps for retaining the printing plate in position on the bed.

In the drawings I have shown a fragmentary portion of a cylinder at 1, and in the face of this cylinder I form spirally-arranged grooves 2 which are undercut to form oppositely projecting flanges 3. The clamp comprises a retaining plate 4 and a base 5, the former being beveled along one or more of its edges, as at 6. This plate is pivotally secured to the base by a screw 7, which latter may be tightened to hold the retaining plate firmly in place. The printing plate is thus held to the bed by the binding action of the beveled edge of the retaining plate and in tightening the screw 55 the printing plate will not buckle.

The base 5 is composed of two parts, corresponding in length, but one of the parts, 8, is of materially less width than the main part of the base. Between these two parts a lateral movement is obtained by means of coiled springs 9 which serve to normally hold the two parts separated, as shown in Figs. 2 and 3. The means shown for limiting the movements of the two parts of the base under the action of the springs consists of studs 10 carried by part 8 and extending into openings 12 in the other part, said studs being flanged at their ends, as at 13, to engage shoulders 14 formed by counterboring the openings.

In applying the clamp, the operator grasps the base between his thumb and one or two of his fingers, and by pressing the two parts together the base may be inserted into a groove of the press bed, and after it clears the flanges 3 the springs will force the two parts against the walls of the groove and beneath the flanges. To remove the clamp it is necessary to provide some means for compressing the parts of the base. In Fig. 5 I have shown a device for this purpose which is substantially in the form of a pair of tweezers 15, and to enable the device to readily engage the opposite sides of the base the ends of the latter are preferably beveled, as at 16. I have shown the two arms of the tweezers as provided with inwardly projecting flanges 17 which serve as stops upon engaging the base.

In Figs. 6 and 7 I have shown a slight modification, the two parts of the base being in part separated by a single spring 9^a encircling a stud 10^a, and the screw 7^a of the retaining plate is intended to work in threaded recesses in the opposite faces of the two base members and thereby, together with the spring, force said members against the walls of the grooves.

The advantages of my invention will be readily appreciated. It will be seen that a clamp constructed in accordance therewith is composed of but very few parts and hence will not readily get out of order, and also that it may be easily inserted into and removed from the grooves of the bed.

The present invention has the further advantage that the printing plate will not buckle in applying the clamps. This is due to the fact that the clamping action is brought about by securing the clamping

plate to its base, and in consequence the latter, together with its spring-pressed portion, is drawn tight against the overhanging flanges of the groove by the act of tightening the clamping plate, which latter is drawn to the printing plate in a line at right angles to the face of the latter. There is no lateral movement of the clamping plate which would tend to buckle the printing plate. The tightening of the latter is sufficient to retain the base in the grooved foundation thereby relieving the spring or springs from the strain which would occur if they were depended upon to retain the base in the groove. In other words, the springs place the base members in position relatively to the overhanging flanges so that the act of tightening the clamping plate will effect the locking of the base member.

20 I claim as my invention:

1. A plate clamp for printing presses comprising a base designed to fit within a grooved foundation, a spring-pressed member carried by said base, a retaining plate 25 designed to be located above the grooved foundation, and a screw connecting the retaining plate to the base, said base and its spring-pressed member being firmly held in the groove as the screw is tightened to cause 30 the retaining plate to engage a printing plate.

2. In combination with a printing bed having a groove therein with overhanging flanges, a clamp comprising a base having oppositely-movable members for engaging 35 the walls of said groove beyond said flanges, yielding means normally holding said members extended, and a retaining plate adjust-

ably connected to said base, which latter is drawn against said flanges by the adjustment of the retaining plate.

3. A plate clamp for printing presses comprising a retaining plate, a base to which said retaining plate is pivotally secured, said base being composed of two parts, one of 45 said parts having openings, and the other of said parts having studs projecting into said openings, and springs interposed between said parts.

4. A plate clamp for printing presses comprising a retaining plate, a base to which said retaining plate is pivotally secured, said base being composed of two parts, one of said parts having openings, and the other of said parts having studs projecting into 55 said openings, and springs surrounding said studs and located in said openings.

5. A plate clamp for printing presses comprising a retaining plate, a base to which said retaining plate is pivotally secured, 60 said base being composed of two parts, one of said parts having openings with shoulders therein, and the other of said parts having studs extending into said openings and provided with flanges for engaging said shoulders, and springs surrounding said studs and 65 engaging the flanged ends thereof for normally holding the parts extended.

In testimony whereof, I have signed this specification in the presence of two subscribing witnesses.

WILLIAM F. MINNICK.
